UNITED STATES PATENT OFFICE.

CHARLES B. GUTHRIE, OF WASHINGTON, DISTRICT OF COLUMBIA.

CONSOLIDATED TARIFF INDEX.

Application filed February 23, 1922. Serial No. 538,647.

To all whom it may concern:

Be it known that I, CHARLES B. GUTHRIE, citizen of the United States, residing at Washington, District of Columbia, have invented certain new and useful Improvements in Consolidated Tariff Indexes, of which the following is a specification.

This invention relates to an improvement in the consolidated tariff index covered by my former Patent No. 1,041,623 granted October 15, 1912, whereby the scope and use of the index are advantageously enlarged.

The consolidated tariff index covered by my patent aforesaid has become standard with the majority of the railroads of the United States and employs certain established fundamentals upon which the present improvements are dependent. These improvements are, therefore, correlated with the underlying and fundamental features of the previously patented index to accomplish certain desirable results.

Among the objects to be attained by the present improvements are the grouping of the leaves of the index into separate tariff sections which relate to various kinds of commodity tariffs, each of said tariff sections being provided with key symbols that are arranged to show the carriers that participate in certain tariffs as initial or originating carriers, one of these separate sections being arranged to show tariffs applicable in the reverse direction where the carriers in a particular territory are delivering carriers, together with key symbols for indicating initial, intermediate, or terminal carriers and a cross reference in the tariff section of the index showing the correlation between the key symbols therein and the symbols in the section that contains the description of the tariffs.

Inasmuch as the improvements for attaining the foregoing general objects are necessarily closely associated with the primary and fundamental features of my former patent, it is believed desirable for the sake of clearness for explaining the present improvements to make reference herein to the general objects and scope of the index as well as to the specific features thereof in so far as they apply to the present improvements.

Accordingly, it will be understood that the proposed joint or consolidated tariff index described herein will show all the tariffs in force on a number of railroads, if possible

all of the railroads operating in the United States, said index to be issued by an agent acting under power of attorney from the various railroads or carriers, and thus overcoming the necessity of each railroad publishing an individual tariff index. I prefer to publish or print the index in sections, each of which relates to the railroads that operate in a certain section of the United States, for example, one section of the index would relate to western lines or western classification territory, another to official classification territory, another to southern classification territory, and another to transcontinental territory. This is only for convenience in filing and handling the index, however, and therefore I wish it to be understood that it is immaterial so far as my invention is concerned whether each issue of the index is published in one volume or in several volumes.

A joint or consolidated tariff index of the character above-described greatly reduces the expense now incurred by each railroad in publishing an individual tariff index, it reduces the space now required by the railroads and by the shippers for filing the individual tariff indices of the different railroads, it enables each railroad to comply strictly with the terms of the Interstate Commerce Commission relative to publishing supplements and reissuing tariff indices by reason of the fact that whenever a railroad makes a change in any of its tariffs it merely has to file a schedule showing such change with the Interstate Commerce Commission as at present, as the agent who issues the consolidated tariff index will maintain an office at Washington or at the city or cities, in which the Government may maintain offices where tariffs are filed. When a railroad makes a change it will notify said agent instead of going to the expense of preparing and issuing a supplement or reissuing the entire tariff index as is now the general practice. It also enables a shipper to ascertain quickly where he can obtain a copy of the particular tariff in which he is interested by reason of the fact that the information in the consolidated tariff index is so condensed and arranged that any one of ordinary intelligence can understand same. The means used to designate the various lines or transportation companies is of such a character that it overcomes the necessity of providing one section to indicate the originating car-

riers and another section to indicate the delivering carriers. Furthermore, such an index shows clearly all of the lines participating under concurrence, and consequently 5 makes it possible for concurring carriers to ascertain and check the concurrences, or authority to issue rates in connection with their lines.

Each section or volume of the consolidated 10 tariff index contains the names of railroads or carriers that issue tariffs applicable to the territory which that particular volume or section of the consolidated index covers, and it also preferably contains the names 15 and addresses of the tariff-issuing officers of said railroads so as to enable a shipper to ascertain the name and address of the person to whom he must write in order to obtain a copy of the published tariff in which he is 20 interested. It also preferably contains the date upon which the tariffs became effective which is very valuable information to carriers and shippers in handling overcharge claims. The tariffs on commodities are 25 preferably divided into specific or special commodity tariffs, miscellaneous commodity tariffs and general class and commodity tariffs.

In the section or portion of the volume that 30 relates to special commodity tariffs a heading is provided for each special commodity, and under each of said headings is arranged the name of the railroad that issues the tariff on said special commodity and the 35 points from and to which the tariff applies. All of the railroads or carriers which participate in said particular tariff are indicated in that section or portion of the index by means of symbols or characters that constitute 40 a key, each symbol or character designating a certain railroad or transportation company. The sections of the index that relate to miscellaneous commodity tariffs and general class and commodity tariffs are 45 arranged in a similar manner, as hereinafter described. Any suitable key may be used for this purpose but I prefer to use one letter of the alphabet with a number or numbers added to designate each railroad, for 50 example—the Adirondack & St. Lawrence Railroad would be designated by a symbol consisting of A', the Albany & Southern Railroad by a symbol consisting of A², and so on. Means is of course provided for 55 explaining or defining the key, or, in other words, stating what railroad or carrier each symbol of the key represents, and in the preferred form of my invention as herein shown said means consists of a column provided 60 with a heading entitled "Key" and arranged in that section or portion of the index that contains the names of the railroads or carriers, the names of the tariff-issuing officers, their addresses, etc., the key symbols being arranged in said column opposite

the names of the railroads which they designate so that the person using the index can ascertain quickly and conveniently the key symbol that is used to designate a particular carrier. It is preferable to use certain groups of symbols to designate certain groups of railroads or transportation companies. For example, the railroads that operate in what is known as "trunk line territory" would be designated by the first 70 five letters of the alphabet with appropriate numbers added; those that operate in what is known as "Central Freight Association territory" by the next five letters of the alphabet and appropriate numbers; those that operate in what is known as "southeastern territory" by the next five letters of the alphabet and appropriate numbers; those that operate in what is known as "southwestern territory" by the next five letters of the alphabet and appropriate numbers; and those that operate in what is known as "transcontinental territory" by the next five letters of the alphabet and appropriate numbers. In this 80 way I am able to designate the lines in different sections of the country by groups of symbols which are similar or have such a relation to each other that a person using the index can tell from the symbols whether the 85 symbol designates a trunk line, a transcontinental line, or so forth. That is to say, as soon as the user sees a symbol containing one of the groups of letters A, B, C, D, or E he knows that the transportation company 90 which said symbol designates is a trunk line. 95

In order to condense the index to a minimum, I distinguish the key symbols that designate originating carriers from the key symbols that designate participating carriers 100 by printing originating carrier symbols in heavy, or black face type, also by prefix INL, and the other symbols in light face type, preceded by the symbol I&D, (indicating intermediate and delivering carrier), in that 105 portion or section of the index in which the 110 information in regard to various tariffs is contained.

In this way I overcome the necessity of providing the index with one section pertaining to the originating carriers and a 115 separate and distinct section pertaining to the participating carriers as is now the general practice. It is not essential, however, that the originating carriers or initial carriers and the other carriers be distinguished 120 from each other in this particular manner as various means could be used for this purpose without departing from the spirit of my invention.

The lines that operate in two different territories, or publish tariffs applicable to two different territories, are designated by a different symbol for each territory. For example, if the Erie Railroad, which is 125 known as a trunk line, operated in, or pub- 130

lished a tariff applicable to the Central Freight Association territory, the symbol C¹ might be used to designate the Erie Railroad in connection with the tariffs applicable to trunk line territory, and the symbol G² might be used to designate the Erie Railroad in connection with tariffs applicable to Central Freight Association territory. This occurs in very few instances, however, or only where a line laps over or runs into different territory from that in which the line operates principally.

I also prefer to use a second key which is separate and distinct from the key just described for designating the various special commodities referred to in the index, said second key being preferably composed of symbols consisting of the letters of the alphabet; for example, agricultural implements and vehicles would be designated by the letter "A;" canned goods by the letter "C;" cement, lime and plaster by the letter "C^b;" chemicals and drugs by the symbol "C^d," etc. The symbols comprising this second key are arranged in a column provided with a heading entitled "Key" opposite the names of articles which the symbols designate so as to define or explain the key, and in certain sections of the index these symbols are used in conjunction with the information relating to the tariffs so as to show the particular kind of goods on which the tariffs apply. Each section or volume of the consolidated index of course contains instructions relating to the use of the index and also descriptions or definitions of the keys as above described so as to show the symbol that is used to designate each railroad and the symbol that is used to designate each special commodity referred to in the index.

I have not herein illustrated the entire consolidated index but only such pages or portions of one section or column of the index that are necessary to show the features which I claim are novel and which make it practicable to consolidate the information in the numerous individual indices now in use into one joint or consolidated index.

Figure 1 of the drawing shows one page of one volume or section of the index which contains the names of railroads or carriers that publish tariffs and operate in the particular section of the United States to which said section or volume relates;

Figure 2 shows a portion of another page which contains the names of special commodities and the key composed of symbols that designate the different special commodities;

Fig. 3 shows a portion of another page which contains the names and addresses of the tariff-issuing officers of the railroads and also the key composed of symbols that designate the different railroads;

Fig. 3^a is a view of a sheet having a heading entitled "List of transportation companies;"

Fig. 4 shows a portion of a page that contains information which shows what railroads issue tariffs on special commodities the points from and to which said tariffs apply, and the carriers or railroads that participate in said tariffs; the originating carriers being preferably indicated by heavy or black-face type and the intermediate or delivering carriers by light-face type;

Fig. 5 shows a portion of a page that relates to miscellaneous commodity tariffs, and shows what railroads issue tariffs on miscellaneous commodities, the points from and to which said tariffs apply, and the carriers that participate in the tariffs;

Fig. 6 shows a portion of a page that relates only to State tariffs, namely, tariffs that apply only to points within a State;

Fig. 7 is a page containing data relating to the change of ownership and control or the receivership of the various transportation companies;

Fig. 8 shows a page giving the list of transportation companies in a specified territory, the same being arranged in numerical key order;

Fig. 9 is a page containing data for initial or originating line's rates used by other carriers, and

Fig. 10 is a view of a sheet containing one of the main sections listing the tariffs of the particular lines included in the section covered by the data on the sheet shown in Fig. 8.

Referring to Fig. 1 of the drawings which illustrates one page of the index, the reference character 1 designates a heading preferably consisting of the words "Issuing carriers" which is arranged above a plurality of vertical columns 2 and 3, the column 2 having a sub-heading 2^a consisting of the word "Transportation company," and the column 3 having a sub-heading 3^a consisting of the letters "F. X. I., No." In the column 2 are arranged the names of different railroads which operate in the section of the United States to which this particular volume of the consolidated index relates, and in the column 3 are arranged numbers which designate the carriers who have conferred power of attorney to the issuing agent under form F. X. I. as prescribed by the Interstate Commerce Commission. Preferably, the term "Item No. 2" is printed at the top of the page for convenience in referring to this section of the index.

The page illustrated in Fig. 2 has a heading 4 which preferably consists of the words "List of commodities," and under said heading are arranged a plurality of vertical columns 5 and 6, the column 5 having a sub-

heading 5^a consisting of the word "Key" and the column 6 having a sub-heading 6^a consisting of the word "Commodity." In column 6 are arranged the names of various special commodities, such, for example, as agricultural implements, canned goods, and cement, lime and plaster; and in the column 5 symbols constituting a key are arranged opposite the names of the special commodities in column 6 so as to show the key symbol that is used to designate each specific commodity. I have herein used the letter A to designate agricultural implements, and vehicles, the letter C to designate canned goods, and the letter C^b to designate cement, lime and plaster, but I do not wish it to be understood that my invention is limited to an index provided with a "key" consisting of these particular symbols or characters for various other symbols or devices could be used to designate the special commodities referred to in the index without departing from the spirit of my invention.

The page illustrated in Fig. 3 has a heading 7 preferably consisting of the words "Carriers in trunk line territory" and the term "Item No. 4" or some other suitable term is preferably printed at the top of the page for the convenience of the user in finding this particular section of the index. Another page or pages, not shown, has a heading entitled "Carriers in C. F. A. territory." Another page or pages, not shown, has a heading consisting of the words "Carriers in southeastern territory," and so on, suitable headings being provided for the carriers in the southeastern, southwestern and transcontinental territories and all of said pages being grouped together so as to form the section or portion of the index that I have arbitrarily called "Item No. 4." Five vertical columns, designated by the reference characters 8, 9, 10, 11 and 12, are arranged under the heading 7, and each of said vertical columns has a sub-heading, the column 8 having a sub-heading 8^a consisting of the word "Key," the column 9 a sub-heading 9^a consisting of the word "Abbreviation," the column 10 a sub-heading 10^a consisting of the words "Name of carrier," the column 11 a sub-heading 11^a consisting of the words "Tariff-issuing officer or title," and the column 12 a sub-heading 12^a consisting of the word "Address." The names of the railroads or carriers that operate in the territory to which the above heading 7 relates are arranged in column 10, the names of the officers of said railroads which issue tariffs, are arranged in the column 11, and the addresses of said officers are arranged in the column 12. The column 9 contains abbreviations for the names of the railroads, and the column 8 contains the symbols or characters that form the "key" used to designate the different railroads the abbreviations and key

symbols, of course, being arranged directly opposite or on the same line with the name of the railroad which they designate.

The page illustrating Figure 3^a has a heading 7^B, preferably consisting of list of transportation companies, and the term, Item No. 4, or some other suitable term is preferably printed at the top of the page for the convenience of the user in finding this particular section of the index. This list to show complete names and corporate titles of the various transportation companies throughout the United States. I have arbitrarily called this Item No. 4. It is six vertical columns designated by the reference characters 7^D, 7^C, 7^E, and 7^F, arranged under the heading 7^B, and each of said vertical columns is sub-headed as per 7^B, 7^E, and 7^F, consisting of the words, "Key," "Abbreviation," "Name of carrier."

The page illustrated in Fig. 4 has a general heading 13, such, for example, as the words Agricultural implements and vehicles, and under this general heading is classified the names of the special commodities that come under said general heading. For example, a sub-heading 13^a is provided for agricultural implements; a sub-heading 13^b is provided for buggies, carriages and wagons, a sub-heading 13^c is provided for cane carts, and so on. Each of the sub-headings 13^a, 13^b and 13^c just referred to is grouped with or arranged over a plurality of vertical columns 14, 15, 16, 17, 18, 19, 20 and 21 arranged side by side and extending across the page, as shown in Figure 4. The three columns 14, 15 and 16 to the left have a heading 140 consisting of the word "Numbers;" the next colmuns 17 and 18 have a heading 170 consisting of the words "Issued by;" the column 19 has a heading 190 consisting of the word "From;" the column 20 has a heading 120 consisting of the word "To;" and the column 21 has a heading 121 consisting of the words "Participating carriers."

In addition to the headings just referred to the columns 14, 15, 16, 17 and 18 have sub-headings 14^a, 15^a, 16^a, 17^a and 18^a; respectively, the heading 14^a consisting of the words "Index No.;" the heading 15^a consisting of the letters "I. C. C.;" the heading 16^a consisting of the words "Other commissions;" the heading 17^a consisting of the words "Road or agent;" and the heading 18^a consisting of the words "Issuing number effective." In the column 17 is arranged the name of the railroad that issues a tariff on agricultural implements; for example the Central of Georgia; in the column 19 is arranged the name of the place or places from which this tariff applies, in the column 18 is arranged the issuing railroad's number and the date the tariff became effective, and in the column 20 the name of the place or places

to which the tariff extends; the column 15 contains the Interstate Commerce Commission number of that particular tariff; the column 14 contains the index number of that particular tariff, (this to be used for convenience of the numeral section), and the column 16 contains any other commission number which has to be specified, for example, the Canadian, or the number of a State commission or commissions. All of the different carriers or railroads which participate in that particular tariff issued by the Central of Georgia are indicated in the column 21 by the key symbols that designate said carriers or railroads. If a number of transportation companies participate in that particular tariff, each company would be designated by its proper key symbol in column 21. Preferably, black-face symbols are used to designate originating carriers and light-face symbols to designate intermediate and delivering carriers. The words (See Item No. 4) are preferably printed in the heading 121 of column 21 so as to form a cross reference or connecting link between the key defined in columns 8, 9 and 10 of the section illustrated in Fig. 3 and the column of the section illustrated in Fig. 4 in which the participating carriers in certain tariffs are designated. For example, a person in looking up the tariff on agricultural implements from Eatonton, Ga., to southeast Mississippi Valley points would find the key symbols A¹, A² and A³ in column 21 of the section or portion of the index illustrated in Fig. 4 of the drawings. He would then refer to the section of the index that I have termed "Item No. 4" and which is illustrated in Fig. 3 of the drawings, and upon examining columns 8 and 10 would find that the key symbol A¹ designates the Adirondack & St. Lawrence R. R.; that A² designates the Albany, Southern R. R.; and that A³ designates the Alexander & Eastern Ry., thus ascertaining the fact that these three railroads participate in the tariff on agricultural implements from Eatonton, Ga., to southeast Mississippi Valley points. He would also know that the Adirondack & St. Lawrence R. R. was the originating carrier or initial carrier because the key symbol A¹ that designates said railroad is printed in black or heavy-face type. I have used the key symbols A¹, A² and A³ in the example above given merely for the purpose of more clearly explaining my index and because these symbols are shown in Fig. 3 of the drawings, but in the actual index the key symbols of the railroads which do actually participate in the tariff mentioned in the example would be specified in column 21 of the section illustrated in Fig. 4.

From the above it will be seen that a consolidated tariff index of the construction above-described enables the carriers, shippers

and all who may contemplate the use of that tariff to quickly determine its scope, and whether or not it would be applicable via the route or reach the territory of the desired shipment. In other words, the tariff is as completely described as far as it is practicable in a directory.

The page illustrated in Fig. 5 has a general heading 22 consisting of the words "Miscellaneous commodity tariffs," and under this general heading are arranged columns 14, 15, 16, 17, 18, 19, 20 and 21 like those shown in Figure 4, and each having the same kind of a heading previously described in connection with Fig. 4. In addition to the vertical columns just mentioned the page illustrated in Fig. 5 is provided with an additional column 23 that has a heading 23^a consisting of the words "Applying on" and also the words (See Item No. 3). Said column 23 contains key symbols which designate certain commodities specified in the section of the index illustrated in Fig. 2 and termed "Item No. 3." For example, the key symbols A, C, C^b and C^e are arranged in column 23 of Fig. 5. By referring to column 5 of the section termed "Item No. 3" the user will see that the key symbol A designates agricultural implements and vehicles, that C designates canned goods, that C^b designates cement, lime and plaster, and that C^e designates cider, vinegar and pickles, and he will thus know that the particular tariff with which these key symbols are associated applies on the articles or the goods previously mentioned.

I have not illustrated the section of the index that relates to general class and commodity tariffs because it is a duplicate of the miscellaneous commodity tariff section illustrated in Fig. 5 except that the column 23 containing the commodity key symbols is not used, owing to the fact that this section relates to general class and commodity tariffs.

The page illustrated in Fig. 6 relates to class and commodity tariffs that are effective between certain points in a State and is provided with columns and headings of the same character as those illustrated in Fig. 5, the only difference between these two pages being that the page illustrated in Fig. 6 has a heading 24 consisting of the name of the State in which State tariffs as distinguished from interstate tariffs are effective.

If a person who contemplates shipping agricultural implements from Eatonton, Ga., to some point in the southeast Mississippi Valley desires to know what the tariff is on such articles he first examines the section of the consolidated index that relates to specific commodities, one page of which is illustrated in Fig. 4. The specific commodities are listed alphabetically in this section so that the user quickly finds the tariff in which he is interested. By referring to

columns 17 and 18 of said section (illustrated in Fig. 4) he finds that the tariff is issued by the Central of Georgia Railroad and that it became effective on Sept. 19, 5 1909. If he desires to know the originating carrier and the various other carriers that participate in said tariff he reads across the page to column 21 in which he finds the key symbols A¹, A² and A³. The cross reference 10 (see Item No. 4) in the heading of column 21 informs the user that he must consult the section of the index termed "Item No. 4" which is illustrated in Fig. 3, in order to ascertain the names of the carriers which 15 said key symbols designate. Turning to this section and examining columns 8 and 9, see Fig. 3 of the drawings, he quickly ascertains the names of the carriers that participate in the tariff in which he is interested. 20 If he desires to obtain a copy of the tariff he consults columns 11 and 12 of the section termed "Item No. 4" so as to ascertain the name and address of the tariff-issuing 25 officer of the railroad that issues the tariff, namely, the Central of Georgia.

In case a user fails to find the tariff in which he is interested in the section that relates to specific commodities, namely, the section illustrated in Fig. 4 of the drawings, 30 he next refers to the section illustrated in Fig. 5 which relates to miscellaneous commodity tariffs. Suppose for example, the same goods above-mentioned are to be shipped but they are to be shipped from 35 Jackson, Miss., to Alexandria, La. In the miscellaneous commodity tariff section illustrated in Fig. 5 the user finds that there is a tariff between the points just mentioned and that it applies on A, C, C^b, and C^e, see column 40 23 of Fig. 5. In order to find out whether or not one of these symbols designates agricultural implements and vehicles, the user follows the instruction (see Item No. 3) in the heading of the column 23 and turns to 45 the section illustrated in Fig. 2, thus finding in columns 5 and 6 of Fig. 2 that the key symbol A designates the goods which he desires to ship. If the user fails to find the tariff in which he is interested in either the 50 specific commodity tariff section or the miscellaneous commodity tariff section he knows that "class" rates will apply, and by referring to the general class and commodity tariff section (not illustrated in the drawing) he will find the tariff in which he is interested. 55 Should a rate be desired which contemplates a movement wholly within a single State, the user examines the section of the index that relates to State tariffs, one 60 page of which is illustrated in Fig. 6.

The page illustrated in Figure 7, arbitrarily called Item No. 5, relating to the change of ownership and control, or receivership of the various transportation 65 companies, under the general heading

"Change of ownership and control, or receivership." This consists of four vertical columns. Item 26 relates to the old name, Item 27 issued and adopted by. The purpose of this section is to show the change of ownership and control, and where tariffs are not amended promptly, showing the new name which can be readily located in this section by reference to the old name of the carrier, and also for convenience, the key 70 reference of the old carrier is referred to wherever the name is changed to such an extent as to make the use of the old symbol out of alphabetical alignment. This also gives information as to the exact date of the 80 change of the corporate title, or the appointment of a receiver, also reference to ICC number which may be filed with the Commission. This section co-relates with what I have arbitrarily called Item No. 4, or "List 85 of transportation companies." Also, in Figure 8, heading arbitrarily called Item No. 6, list of transportation companies in the southern territory, arranged in key order, as shown in Figure 8, Item 29. This arranged with key Item 30 and transportation company Item 31. The key numbers to run in numerical order. I have illustrated this in a particular southern territory, but it may be used in eastern, western, or any other 90 sub-division territory. The purpose of this item is that a seeker of information as to application of a tariff shown in Figure 4, 5 or 6, may readily determine what the name of that company is by observing the numerical reference to the key number, and co-relates with Figures 4, 5 and 6. Of course, if a person desires the name of the carrier in the first instance, that is obtained as illustrated in Figures 3 and 3^a, whichever plan 105 may be used. It enables a seeker of information to have two avenues of locating a desired name of a transportation company.

The page illustrated in Figure 9 has the heading preferably: "Initial or originating lines rates issued by other carriers," consisting of six perpendicular columns indicated by columns 33, 34, and 35. The use of this particular feature named in Item 8, to designate the trunk line or member carrier 110 that issues tariffs for a smaller road. The key symbol used by the small line is co-related with Figures 4, 5 and 6 as illustrated, and it enables the shipper or anyone seeking information, where to look for the rates 115 published by the small road. It is often the case that two or more carriers issue rates from a single smaller line and the purpose 120 of this section is to clarify this situation.

The page relating to Figure 10 will make 125 a decided improvement on listing tariffs in territories where a great number of local tariffs are employed, by an arrangement of first listing the railroad or transportation companies in alphabetical order, and under 130

each heading of the transportation companies will appear reference to other carriers or agents that issue tariffs from this carrier's station (numeral 51) also the 5 tariffs of that company which it issues, and in which that road, or some other carrier for which the index is issued is an initial carrier. To describe Figure 10, it will consist of twelve vertical columns with title 10 headings as indicated by numerals 36, 37, 38, 39, 40 and 41, with suitable sub-heading as indicated by 43, 44, 45, 46, 47, 48, 49 and 50. The tariffs will be listed in these 15 columns, first specifying the specific commodities, then general commodities, class and commodities, class tariffs, followed by miscellaneous circulars. This is an improvement over the commodity indexing described in Figures 4, 5 and 6, as it will be 20 my purpose to arrange the consolidated index in three sections, the first section to be as described in Figure 10, showing tariffs in which the lines are initial carriers, and in section 2, which is similar to this Figure 25 10, but not herein illustrated to indicate the tariffs in alphabetical order of the transportation companies in which traffic is delivered to the lines for which the index is issued. To explain it more clearly, while its 30 intent is to issue for all the territories, to make the point clear, I will describe the southern book. The first section will indicate tariffs applicable from, at, or within the south, while section 2 will list the tariffs 35 applicable to the south. This same plan to be followed in the indices of other territories.

The foregoing description covers and describes a complete tariff index for the listing 40 of all tariffs applicable from, to or via any of the transportation companies operating in the United States. However, it will of course be understood that where it is desirable to show tariffs applicable only in one 45 direction it may be more convenient to make the separate tariff sections in two independent books or volumes. In all other respects however, the novel features of the index remain unchanged.

I claim:—

1. A consolidated index comprising groups of leaves bearing suitable printed matter arranged to form separate tariff sections which relate to various kinds of commodity tariffs, each of said tariff sections 55 being provided with key symbols that are arranged to show the carriers that participate in certain tariffs as initial or originating carriers, and a separate section which is arranged to show tariffs applicable in the 60 reverse direction where the carriers in a particular territory are delivering carriers, and key symbols to indicate initial, intermediate, or terminal carriers, and the cross reference in the tariff section of the index 65 for showing the co-relation between the key symbols therein, and the symbols in the section that contains the descriptions of the tariffs.

2. A consolidated tariff index comprising 70 groups of leaves bearing suitable printed matter secured together and arranged to form separate tariff sections, which relate to the initial or originating lines by key reference, a key for indicating the name of the 75 transportation company which allows or permits other carriers to issue its rates, and means explaining said key co-related with each of said separate tariff sections.

3. A consolidated tariff index comprising 80 separate tariff sections consisting of groups of leaves, means on the leaves of some of the groups showing the tariffs issued by transportation companies, a key composed of symbols representing the companies or 85 carriers and grouped with said means for showing the carriers that participate in the said various tariffs, and means on the leaves of any group for explaining said key or defining which carrier each symbol of the 90 key designates.

In testimony whereof I hereunto affix my signature in the presence of two witnesses.

CHARLES B. GUTHRIE.
